D21417

UNITED STATES PATENT OFFICE.

WILLIAM SCHOTT, OF BROOKLYN, NEW YORK.

DESIGN FOR A NEEDLE-HOLDER.

SPECIFICATION forming part of Design No. 21,417, dated March 22, 1892.

Application filed February 23, 1892. Serial No. 422,586. Term of patent 7 years.

To all whom it may concern:

Be it known that I, WILLIAM SCHOTT, of Brooklyn, in the county of Kings and State of New York, have invented and produced a certain new, original, and useful Design for Needle-Holders, of which the following is a description, reference being made to the accompanying drawing, which fully illustrates the design.

- 10 The essential feature of the design consists of its general outline, which is substantially that of a segmental block having a zonular peripheral surface and a flat base at right angles to its plane sides.
- 15 The peripheral or zone face *a* of this holder is represented as of a puffed or cushion-like form.

The sides *b* of the holder are plate-like in form, the lower right-line edges *c* of the same coinciding with the flat base *d*, and the upper curved edges *e* fall within the curve of the peripheral face *a*. Each of these sides bears surface decoration, which at the curved edges *e* consists of the wavy or scalloped line *f* and across the face of the sides of the conventionalized rays *g*, springing from a common center at the middle of the base.

What is claimed as new is—

The design for a needle-holder, substantially as herein described and shown.

WILLIAM SCHOTT.
